(57) **CLAIM**

The ornamental design for a cutlery carousel, as shown and described.

DESCRIPTION

FIG. 1 is a top, front, and right side perspective view of a cutlery carousel showing my new design, the utensils are shown in broken lines for illustrative purposes only and form no part of the claimed design;

FIG. 2 is a rear elevational view thereof;

FIG. 3 is a left side elevational view thereof;

FIG. 4 is a top plan view thereof;

FIG. 5 is a bottom plan view thereof;

FIG. 6 is a top, front and right side perspective view of an alternate embodiment of FIG. 1, the difference being the change in the slot areas on the side portions, the utensils are shown in broken lines for illustrative purposes only and form no part of the claimed design; and,

FIG. 7 is a top plan view of FIG. 6.
